UNITED STATES PATENT OFFICE.

WILLIAM JACOBY AND VENNIE Y. JACOBY, OF FULDA, MINNESOTA, ASSIGNEES OF FORTY-NINE ONE-HUNDREDTHS TO WALTER E. REUSSE, OF FULDA, MINNESOTA.

AUTOMATIC MAGAZINE-HAMMER.

1,163,409.

Specification of Letters Patent.

Patented Dec. 7, 1915.

Application filed March 24, 1915. Serial No. 16,602.

To all whom it may concern:

Be it known that we, WILLIAM JACOBY and VENNIE Y. JACOBY, citizens of the United States, residing at Fulda, in the county of Murray and State of Minnesota, have invented certain new and useful Improvements in Automatic Magazine-Hammers; and we do hereby declare the following to be a full, clear, and exact description of the invention, such as will enable others skilled in the art to which it appertains to make and use the same.

Our invention has for its object to provide an improved hammer or hatchet of the type having in its handle a nail magazine and suitable mechanism for automatically removing the nails from the magazine and delivering the same into a position to be set by a blow delivered by the hammer or hatchet.

To the above end, generally stated, the invention consists of the novel devices and combination of devices hereinafter described and defined in the claims.

In the accompanying drawings, which illustrate the invention, like characters indicate like parts throughout the several views.

Referring to the drawings:—Figure 1 is a view in side elevation of a lathing hatchet, having the invention incorporated therein; Fig. 2 is a longitudinal section taken on the line $X^2 X^2$ of Figs. 1 and 3; Fig. 3 is a view principally in longitudinal section, taken on the line $X^3 X^3$ of Fig. 2; Fig. 4 is a front elevation of the hatchet; Fig. 5 is a view corresponding to Fig. 4 with the exception that the so-called nail set and escapement actuator is removed; Fig. 6 is a plan view of the so-called nail set and escapement actuator; Fig. 7 is a front elevation of the same; Fig. 8 is a transverse section taken on the irregular line $X^8 X^8$ of Fig. 3; Fig. 9 is a detail view principally in longitudinal section taken on the line $X^9 X^9$ of Fig. 3; Fig. 10 is a view corresponding to Fig. 9 with the exception that certain parts are shown in different positions; Fig. 11 is a detail view in transverse section taken on the line $X^{11} X^{11}$ of Fig. 3; and, Fig. 12 is a detail view in transverse section taken on the line $X^{12} X^{12}$ of Fig. 3.

The numeral 1 indicates the head of the lathing hatchet, preferably made from two drop forgings rigidly connected by rivets 2, and having integrally formed with one

of said forgings a hatchet blade 3. Within the head 1 is formed a handle receiving eye 4, and a feed chamber 5. This eye 4 does not extend completely through the head 1, and the feed chamber 5 extends in front thereof and to points both above and below said eye. The front of the feed chamber 5 is open below the axis of the eye 4.

Mounted within the eye 4 is a handle 6 rigidly secured to the head 1 by rivets 7. In the outer end portion of this handle 6 is formed a nail magazine 8 and, in the intermediate portion thereof, above its horizontal center, is a nail arighting chamber 9, having communication with said magazine. The top of the arighting chamber 9 is open and normally closed by a saddle plate 10, which embraces the sides of the handle 6 and is detachably secured thereto by screws 11. Obviously, access may be had to the arighting chamber 9 by removing the saddle 10.

The outer open end of the magazine 8 is normally closed by a gravity actuated gate 12, hinged to the top of said magazine, arranged to swing inward, and of a length greater than the height of said magazine, which prevents the gate 12 from swinging outward through the open end of the magazine. By thus mounting the gate 12, the same, when closed, stands in an oblique position (see Fig. 3); and the nails Z, within the magazine 8, hold the door closed.

Formed in the handle 6, below the arighting chamber 9, is a longitudinally extended guide channel 13 which extends the full length of said chamber and into the feed chamber 5. Mounted in the guide slot 13, near the upper surface thereof, is a pair of horizontally spaced guide rails 14, as shown, made from a single piece of wire bent upon itself. The rear or connected ends of the rails 14 rest upon a ledge 15 formed in the handle 6 at the entrance of the magazine 8 to the arighting chamber 9. At their forward or free ends the rails 14 are curved downwardly and rest on the bottom of the eye 4 at a point where the same enters the feed chamber 5.

Mounted in the bottom of the arighting chamber 9 is a metal plate 16 having a longitudinally extended nail arighting slot 17, which directly overlies the rails 14. The ends of this plate 16 are bent downward to afford flanges 18 and 19, which rest on the

rails 14 and support the plate 16 thereabove. A rivet 20, passed through the ledge 15, between the rails 14, and through the plate 16, securely holds said plate in position, and which plate, in turn, by its flange 18, holds the rear ends of the rails 14 onto the ledge 15. The rivet 20 and ledge 15 also hold the rails 14 against endwise movement in either direction. The forward end of the plate 16 is held in position with its flange 19, which is notched to afford a clearance passage between the rails 14, resting directly on said rails, by a flange 21 formed with the saddle 10, and extending through the arighting 15 chamber 9.

The width of the slot 17 is sufficient to permit the bodies of the nails to pass therebetween during the arighting thereof, but not their heads, which rest on the plate 16 with their bodies hanging freely between the rails 14 and through the guide slot 13. The slot 17, at several longitudinally spaced points, (as shown in Figs. 2 and 3) is widened to afford nail escape passages 22 through which the heads of the nails, supported on the plate 16, may drop. The nails, in dropping through the passages 22, are again intercepted by their heads coming in contact with the underlying rails 14, on which rails the nails are supported for movement through the slot 13 to the feed chamber 5. The purpose of the plate 16 and escape passages 22 is to prevent the nails from clogging between the rails 14 as they are arighted.

During the travel of the nails on the rails 14 toward the feed chamber 5, they are successively engaged by a pair of escape dogs 23, as shown in the form of upwardly and forwardly inclined pins, mounted in seats 24 in the handle 6, forward of the arighting chamber 9 and loosely resting one on each of the rails 14. These escape dogs 23 will lift to permit the nails to pass thereunder during their forward travel, but will not let them pass in a return movement. After the nails have passed the escapement dogs 23, they are intercepted by an escapement which will presently be described.

50 Mounted on the front face of the head 1, and closing the feed chamber 5, is a combined nail starter and escapement actuator in the form of a plate 25, pivotally mounted for oscillatory movement in a vertical plane. 55 As shown, the pivotal support for the plate 25 is in the form of a stud 26 on the head 1 and which projects through a perforation 27 in said plate. This pivotal connection for the plate 25 is located at one side of the vertical center of said plate and at substantially the vertical center thereof. A flat spring 28, pivoted at 29 to the head 1 of the hatchet, above the plate 25, bears against said plate and its lower end is bifurcated to receive a 65 pin 30 on said plate above the pivot 26 for

oscillatory movement with the plate 25. This spring 28 yieldingly and frictionally holds the plate 25 in either of its extreme positions.

The escapement 31, previously referred to, 70 is U-shape and, as shown, is bent from a single piece of wire. The prongs of this escapement 31 are passed through a pair of horizontally aligned perforations in the plate 25 near the top thereof. The transverse portion 75 of the escapement 31 engages the outer face of the plate 25 and the spring 28 bears directly on said transverse portion. The prongs of the escapement 31 embrace the curved front ends of the rails 14, and their 80 free ends are bent laterally inward to afford a pair of points 32 and 33. These points slightly overlap one another, and the point 32 is spaced in advance of the point 33 to permit the body of a nail to pass therebetween. The escapement points 32-33 extend below the rails 14 and normally the point 32 projects across the path of movement of the nails between the rails 14. During the oscillatory movements of the plate 25, 90 the escapement is actuated to separate the foremost nail from the main column in the well known manner.

Each nail, after having passed the escapement points 32-33, continues its forward 95 movement over the rails 14 until the same comes in contact with an oblique stop 34 formed by slotting the head 1 below the eye 4 to afford a continuation of the slot 13. Under the lifting movement of the hatchet 100 to deliver a blow, the nail, resting on the stop 34, is thrown by centrifugal force to the top of the feed chamber 5. On striking the top of the feed chamber 5, the nail drops, under the action of gravity, into a contracted discharge passage 35 formed in the head 1 below the feed chamber 5. The rear wall of the feed chamber 5, above the guide slot 13, is formed oblique to afford a deflecting surface 36, with which the nails engage, 110 when thrown from the stop 34, to deflect the same to the front of the feed chamber 5. At the junction of the side walls of the feed chamber 5 with the discharge passage 35, are deflecting surfaces 37, with which the points 115 of the nails engage to cause the same to enter the said discharge passage. The discharge passage 35 is wide enough to receive the bodies of the nails, but not their heads, so that the nails entering said discharge passage are supported therein by the engagement of their heads with the deflecting surfaces 37. At the back of the discharge passage 35 is a deflecting surface 38 which causes the nails, upon entering said discharge 125 passage, to travel forward into a position, as shown in Fig. 3, with their points projecting below the striking surface of the hatchet and their heads directly underlying the striking surface 39 of the combined nail 130

starter and escapement actuator. The nails, in assuming the position just described, are prevented from passing entirely out of the discharge passage 35 by a depending extension 40 on the plate 25, which normally extends obliquely across the discharge passage 35, as best shown in Fig. 4.

A depending stop lug 41 on the striking face 39 of the plate 25 engages the head 1 to limit the oscillatory movement of the plate 25 in one direction, and the plate extension 40 engages one of the side walls of the discharge passage 35 to limit the oscillatory movement of said plate in the other direction. In the sides of the head 1 are formed eight openings 42 located substantially opposite the points 32-33 of the escapement. A discharge opening 43 is formed in the back of the head 1, above the deflecting surface 38, opens into the feed chamber 5, and through which opening surplus nails are discharged to prevent clogging of the discharge passage 35.

As shown, the plate 25 and its extension 40 are mounted in a recess formed in the front of the head 1 and the overlying shoulder of said head affords an abutment 44 for the plate 25 to resist driving strains in partly driving nails and thereby relieves the strain 30 on the pivot stud 26. Obviously, by bending the spring 28 out of engagement with the pin 30, said spring may be turned into a position, as shown in Fig. 5, and the plate 25, together with the escapement 31, re-35 moved from working positions.

Operation: The operation of the improved nail magazine hammer may be briefly described as follows:—The magazine 8 is filled with nails by holding the handle of the hatchet in an upright position with the head 40 downward. In this position of the handle, the gate 12 swings open under the action of gravity, allowing the nails to be poured into the magazine 8 and into the arighting chamber 45 9. Then by turning the handle 6 into a substantially horizontal position and giving the same a slight shake, which causes a number of the nails to drop into the arighting slots 17 and 13, where certain of the nails will 50 work through the escape passages 22 and drop onto the guide rails 14. From thence the nails will work along the guide rails 14, under the escapement dog 23, until intercepted by the escapement finger 32. The 55 operator then oscillates the plate 25, by means of his fingers, to actuate the escapement, releases the first nail from the main column, and sets the plate 25 in a position shown in Fig. 4 with the extension 40 cutting off the discharge passage 35. The nail just released by the escapement, will continue its travel, under the action of gravity, along the curved front ends of the rails 14, and be deposited thereby onto oblique stops 34. Then 60 by giving the hatchet a slight upward swing,

said nail will be thrown by centrifugal force from the stop 34 into the feed chamber 5 and drop, under the action of gravity, into the discharge passage 35, where it will be held by the extension 40 with its point projecting below the striking surface of the head 1 and with its head underlying the striking surface 39 of the nail starter. The hatchet is now ready for use. The first blow of the hatchet will bring the striking surface 39 of the nail starter into contact with the nail in the discharge passage 35, thereby partly driving the same. The action of this blow on the plate 25 will oscillate the same on its pivot 26, thereby opening the discharge passage 35 and actuating the escapement 31 to release a second nail. In the lifting of the hatchet for the second blow, the initial movement is toward the operator, to free the hatchet from the partly driven nail through the open discharge passage 35. This second upward stroke of the hatchet will throw the second nail from the stop 34, as previously described, into the feed chamber 5. As the second blow is delivered by the hatchet to drive the partly driven nail home, the force thereof will cause the plate 25 to swing on its off-set pivot 26 into its normal position, as shown in Fig. 4, thereby cutting off the escape of the second nail in the discharge 95 passage 35 and actuating the escapement 31 to cause the third nail of the main column to move into a position between the points 32-33 where the same will be released by the escapement under the action of the blow 100 delivered to partly drive the second nail.

From the foregoing description, it is evident that only two blows of the hammer are required to drive a nail; the first blow to partly drive the same, and the second blow 105 to drive the nail home. Before all of the nails in the magazine are used, others should be added, so that the nails are fed from the magazine to the nail starter automatically and without interruption.

By reference to Fig. 4, it is important to note that when the plate 25 is in a releasing position, the lug 41 will move back of a projecting lip 45 to prevent the plate 25 from being pulled from the stud 26, in case the extension should catch on a partly driven nail as the hammer is withdrawn therefrom.

What we claim is:—

1. The combination with a hammer having a nail magazine, of means for discharging the nails from said magazine, and a nail starter adapted to intercept and hold the nails discharged from said magazine, arranged to be actuated by the first blow delivered by the hammer, to partly drive and release the nail held thereby, and to be returned to normal position by the second blow delivered by the hammer for driving the partly driven nail home.

2. The combination with a hammer hav-

ing a nail magazine, of means for discharging the nails from said magazine, a nail starter adapted to intercept and hold the nails discharged from said magazine, arranged to be actuated by the first blow delivered by the hammer, to partly drive and release the nail held thereby, and to be returned to normal position by the second blow delivered by the hammer for driving the partly driven nail home, and a friction device for holding said nail starter in either of its extreme positions.

3. The combination with a hammer having a nail magazine, of an escapement, means for actuating said escapement, and a nail starter adapted to intercept and hold the nails discharged from said magazine by said escapement, said nail starter arranged to be actuated by a blow delivered by the hammer to partly drive and release the nail held thereby.

4. The combination with a hammer having a nail magazine, of an escapement, and a nail starter adapted to intercept and hold the nails discharged from the magazine by said escapement, said nail starter arranged to be actuated by the first blow delivered by the hammer to partly drive and release the nail held thereby, and said escapement arranged to be actuated by alternate blows delivered by the hammer to release a nail from the magazine.

5. The combination with a hammer having a nail magazine, of an escapement, and a nail starter arranged to intercept and hold the nails discharged from the magazine by said escapement, said nail starter arranged to be actuated by the first blow delivered by the hammer to partly drive and release the nail held thereby, and said escapement arranged to be actuated by the movement of said nail starter.

6. The combination with a hammer having a nail magazine, of a nail starter, and an escapement carried by said nail starter, said nail starter adapted to intercept and hold the nails discharged from the magazine by said escapement, arranged to be actuated by the first blow delivered by the hammer to partly drive and release the nail held thereby, and to move said escapement into a cut-off position, said nail starter also arranged to be returned to normal position by the second blow delivered by the hammer for driving the partly driven nail home, the movement of said nail starter to normal position serving also to move said escapement into a nail releasing position.

7. The combination with a hammer having a nail magazine, of a nail starter, an escapement carried by said nail starter, and a stop for intercepting the nails, discharged from said magazine by said escapement, the nails held by said stop being released therefrom by the lifting stroke of the hammer,

and again intercepted and held by said nail starter, said nail starter arranged to be actuated by the first blow delivered by the hammer to partly drive and release the nail held thereby, and to move said escapement into a cut-off position, and arranged to be returned to normal position by the second blow delivered by the hammer for driving the partly driven nail home, the movement of said nail starter to normal position serving also to move said escapement into a nail releasing position.

8. The combination with a hammer having in its handle a nail magazine, an arighting chamber, and a guide slot, and having in its head a feed chamber, and a discharge passage, of a nail starter mounted on the head of said hammer, an escapement actuated by said nail starter for action on the nails in passing through said guide slot, under lifting movement of the hammer and discharged by said escapement, the nails held by said stop being removed therefrom, under lifting movement of the hamer and discharged into said feed chamber, the nails discharged into said feed chamber being intercepted and held in said discharge passage by said nail starter, said nail starter arranged to be actuated by the first blow delivered by the hammer to partly drive and release the nail held thereby, and to move said escapement into a cut-off position, said nail starter also arranged to be returned to normal position by the second blow delivered by the hammer for driving the partly driven nail home, the movement of said nail starter to normal position serving also to move said escapement into a nail releasing position.

9. The combination with a hammer having in its handle a nail magazine, an arighting chamber, and a guide slot, and having in its head a feed chamber, and a discharge passage having a deflecting surface, of a nail starter mounted on the head of said hammer, an escapement actuated by said nail starter for action on the nails in passing through said guide slot, and a stop for intercepting the nails discharged by said escapement, the nails held by said stop being removed therefrom, under lifting movement of the hammer and discharged into said feed chamber, the nails discharged into said feed chamber entering said discharge passage and being deflected thereby into engagement with said nail starter, said nail starter arranged to be actuated by the first blow delivered by the hammer to partly drive and release the nail held thereby in the discharge passage, and to move said escapement into a cut-off position, said nail starter also arranged to be returned to normal position by the second blow delivered by the hammer for driving the partly driven nail home, the movement of said nail

starter to normal position serving also to move said escapement into a nail releasing position.

10. The combination with a hammer having in its handle a nail magazine, an arighting chamber, having a slotted bottom with escape passages therein, and guide rails underlying said escape passages, and having downwardly inclined delivery ends, said hammer having in its head a feed chamber, and a discharge passage, of a nail starter mounted on the head of said hammer, an escapement dog coöperating with said rails to prevent return movement of the nails, an escapement actuated by said nail starter for action on the nails after passing said escapement dog, and a stop for intercepting the nails discharged by said escapement onto the delivery ends of said rails, the nails held by said stop being removed therefrom, under lifting movement of the hammer and discharged into said feed chamber, the nails discharged into said feed chamber being intercepted and held in said discharge passage by said nail starter, said nail starter arranged to be actuated by the first blow delivered by the hammer to partly drive and release the nail held thereby, and to move said escapement into a cut-off position, said nail starter also arranged to be returned to normal position by the second blow delivered by the hammer for driving the partly driven nail home, the movement of said nail starter to normal position serving also to move said escapement into a nail releasing position.

11. The combination with a hammer having in its handle a nail magazine, an aright-

ing chamber, and a guide slot, and having in its head a feed chamber, and a discharge 40 passage, of a nail starter mounted on the head of said hammer, an escapement actuated by said nail starter for action on the nails in passing through said guide slot, and a stop for intercepting the nails discharged by said escapement, the nails held by said stop being removed therefrom, under lifting movement of the hammer and discharged into said feed chamber, the nails discharged into said feed chamber being 45 intercepted and held in said discharge passage by said nail starter, said nail starter arranged to be actuated by the first blow delivered by the hammer to partly drive and release the nail held thereby, and to 50 move said escapement into a cut-off position, said nail starter, also arranged to be returned to normal position by the second blow delivered by the hammer for driving the partly driven nail home, the movement 55 of said nail starter to normal position serving also to move said escapement into a nail releasing position, said feed chamber having a discharge opening through which surplus nails are discharged. 60 65

In testimony whereof we affix our signatures in presence of two witnesses.
